UNITED STATES PATENT OFFICE.

ARTHUR MARTIN, OF PARIS, FRANCE.

DESIGN FOR WALL-PAPER.

SPECIFICATION forming part of Design No. 28,109, dated December 28, 1897.

Application filed October 26, 1897. Serial No. 656,468. Term of patent 7 years.

To all whom it may concern:

Be it known that I, ARTHUR MARTIN, of Paris, France, have invented and produced a new and original Design for Wall-Paper, of which the following is a specification, reference being had to the accompanying drawing, forming a part thereof, in which is represented a plan view of a fragment of wall-paper embodying the new design.

10 The design which is produced upon wall-paper X is particularly adapted for wall-paper printed in relief; and it consists of a festooned crescent-shaped garland A, composing alternate floral and ribbon sections, bouquets A' 15 being represented as tied at the extremities of the garland. A centerpiece B appears between the bouquets and over the center of the garland. The centerpiece consists of a

foliate vase represented as supporting a parent stem having oppositely-drooped laterals, both the parent stem and the laterals bearing flowers and foliage at their outer ends. Below the center of the garland the stems of foliate scrolls D are crossed, and the foliate scrolls curve upward, one at each side of the center of the garland, their upper ends returning in opposite directions. At the crossing of the foliate scrolls a bow, a quiver, and a torch are grouped.

I claim—

30 The design for wall-paper herein shown and described.

ARTHUR MARTIN.
